(Cl. D14—3)

To all whom it may concern:

Be it known that I, Walter C. Bauer, a citizen
of the United States, residing at Chevy Chase,
Maryland, have invented a new, original, and
ornamental Design for Portable Lubrication Unit,
of which the following is a specification, reference
being had to the accompanying drawing, forming
part thereof.

Figure 1 is a rear perspective view of a port-
able lubrication unit showing my new design; and
Figure 2 is a front perspective view thereof.

I claim:

The ornamental design for a portable lubrica-
tion unit, as shown.

WALTER C. BAUER.
